(57) **CLAIM**

(21) Appl. No.: **29/292,299**

The ornamental design for a “beer can shaped illumination device for guest check presenters, menus, and wine lists,” as shown and described.

(22) Filed: **Oct. 5, 2007**

DESCRIPTION

(51) **LOC (8) Cl. 26-05**

FIG. 1 is a perspective view of a beer can shaped illumination device for guest check presenters, menus, and wine lists, showing my new design;

(52) **U.S. Cl. D26/60**

FIG. 2 is a front elevational view thereof;

(58) **Field of Classification Search D26/60-66,**

FIG. 3 is a rear elevational view thereof;

D26/51, 107, 37, 38, 46, 48, 94, 125, 26;

FIG. 4 is a left side elevational view thereof;

362/116, 200, 120, 119, 183, 196, 208, 205,

FIG. 5 is a right side elevational view thereof;

362/98, 99, 154, 253; D19/34

FIG. 6 is a top plan view thereof; and,

See application file for complete search history.

FIG. 7 is a bottom plan view thereof.

(56) **References Cited**

The broken line showing of a guest check presenter in FIG. 1 is for illustrative purposes only and forms no part of the claimed design. The broken line showings of an Attachment Clip in FIGS. 3-7 are for illustrative purposes only and form no part of the claimed design.
